UNITED STATES PATENT OFFICE.

GUSTAV SCHOENEMANN, OF NEW YORK, N. Y.

DESIGN FOR A JEWELRY-BOX.

Specification forming part of Design No. 5,599, dated March 5, 1872.

Specification describing a new and original Design for a Jewelry and Silver-ware Box, invented by GUSTAV SCHOENEMANN, of the city, county, and State of New York.

The drawing represents a perspective view of my new design for a box.

This invention relates to a new form of box for retaining jewelry or silver-ware; and consists in rounding the top of the same in peculiar manner.

The box A is of rectangular outline, and

has a flat bottom and flat vertical sides *a a*. The top *b*, however, is arched in such manner as to be lowest at the corners *c c*, and highest at the middle, thereby making the upper edges of the sides arched also, as shown.

I claim as my invention—

The design for the box A, as shown.

G. SCHOENEMANN.
